INTERLOCKING FASTENER

Hermon G. Gentry, Atlanta, Ga., assignor to The Mead Corporation, a corporation of Ohio
Filed June 19, 1963, Ser. No. 283,935
5 Claims. (Cl. 24—204)

This invention relates to interlocking means for article carriers and the like and more particularly is directed to means for securing one edge of a yieldable panel to an adjacent complementary edge of an adjacent yieldable panel, the two panels being disposed in substantially coplanar relationship.

In article carriers constructed of paperboard for example and which are of the wrap-around type, it is customary to secure the ends of the wrapper together by suitable means such as glue, locking tabs and the like. Where the ends of the wrapper are secured by glue, it is customary to apply the glue throughout the length of the overlapping edges. While it may be advantageous to secure the end edges of such a wrapper along the entire length thereof, gluing operations require a certain amount of setting time and hence impose a limitation on the speed of performance of a packaging operation using glue.

In wrapper-type article carriers using locking tabs, the overlapping end edges are not secured together along the entire length thereof according to present practice although locking tabs inherently afford highspeed packaging because of the elimination of glue setting time.

A principal object of this invention is to provide an improved interlocking means for wrapper type carriers which utilizes locking tabs formed along the edges of the ends of the wrapper to be secured together and extending throughout the length thereof and by so doing to form a junction along the entire length of the overlapping ends of the wrapper while eliminating the time required for the setting of glue.

Another object of this invention is the provision of an unusually strong securing means for adjoining adjacent edges of two substantially coplanar panels and which effectively prevents substantial relative motion in the planes of the panels in any direction.

The invention in one form as applied to a pair of adjacent generally coplanar yieldable panels comprises a plurality of locking tabs disposed along an edge of one of the panels in spaced relation, locking tabs disposed along the adjacent edge of the other panel and disposed in staggered relation thereto so that the locking tabs of one panel are interposed between the locking tabs of the other panel when the lock is secured.

For a better understanding of the invention reference may be had to the following detailed description taken in conjunction with the accompanying drawings in which FIG. 1 is a perspective view of a wrap-around type of carrier depicted in the setup condition with packaged articles such as bottles shown in dotted lines and to which the invention is applicable; FIG. 2 is a plan view of a blank from which the carrier depicted in FIG. 1 is formed; FIG. 3 is an enlarged fragmentary view from the bottom showing the interrelationship of the zipper-type locks of FIGS. 1 and 2 formed on an edge of one panel with similar locks formed on an edge of the other panel; FIG. 4 is a view similar to FIG. 3 but showing the locks in unlocked condition; and in which FIGS. 5 and 6 are views similar to FIG. 4 but showing alternative lock constructions in the disengaged position.

While the invention is shown as applied to an article carrier, it will be understood that it is not limited thereto and has other applications as well.

With reference to FIGS. 1 and 2 the numeral 1 indicates the top panel of the carrier while the numerals 2 and 3

2

designate shoulder panels which are foldably joined respectively to top panel 1 along fold lines 4 and 5. Foldably joined to shoulder panel 2 along fold line 6 is a side panel 7 while a similar side panel 8 is foldably joined to shoulder panel 3 along fold line 9. Bottom sloping panel 10 is foldably joined along line 11 to the bottom edge of side panel 7 while a similar sloping panel 12 is foldably joined along fold line 13 to the bottom edge of side panel 8. Bottom lap panel 14 is foldably joined to sloping panel 10 along fold line 15 and a similar lap panel 16 is foldably joined to sloping panel 12 along fold line 17.

In order to facilitate carrying the package depicted in FIG. 1, a pair of finger gripping tabs 18 and 19 are struck out of top panel 1 and may be folded inwardly along their respective fold lines 20 and 21.

For the purpose of receiving the necks of packaged bottles for example, a plurality of scalloped openings 22-27 may be formed in known manner in the top panel 1 and form resilient apertures for cushioning the necks of the packaged bottles shown dotted and designated in FIG. 1 by the letter B.

For receiving the bottom rims of the packaged bottles, a plurality of apertures 28, 29 and 30 are formed within sloping panel 10 and function in known manner to aid in securing the bottles B within the wrapper against inadvertent displacement therefrom. Similarly openings 31, 32 and 33 are formed in sloping panel 12.

To draw the wrapper depicted in FIG. 2 tightly about a group of packaged items such as are designated by the letter B in FIG. 1, a pair of tightening apertures 34 and 35 are formed in lap panel 14 and similar tightening apertures 36 and 37 are formed in lap panel 16. If desired the tabs defined by apertures 34-32 may be retained as indicated in the drawing. As is well understood in the art, suitable machine elements enter apertures 34 and 35 and move inwardly in opposition to similar machine elements disposed within tightening apertures 36 and 37 so as to draw the lap panels 14 and 16 snugly toward each other and into generally coplanar relationship thereby to condition the interlocking means generally designated by the numeral 38 on lap panel 14 for cooperative relationship to the interlocking means generally designated by the numeral 39 formed on lap panel 16.

As is shown in FIG. 2 the locking means 38 comprises a plurality of locking tabs 40-44 which are disposed along an edge of lap panel 14. The locking tabs are provided with score lines and abutment shoulders. As can be seen in FIG. 2 locking tab 40 is provided with a single medial longitudinal slit 45 having its outer end spaced from the tip of the tab and arranged to impart a measure of flexibility without substantially weakening the tab. Similarly locking tabs 41-44 are provided with medial cut lines 46-49, respectively.

The structure formed along the edge of lap panel 16 and generally designated by the numeral 39 is similar to the interlocking means formed along the lap panel 14 and designated by the numeral 38. For example, interlocking means 39 comprises a plurality of locking tabs 50-53 having medial slits 54-57, respectively.

FIG. 3 shows fragments of the locking structure 38 and 39 in interlocking relationship as viewed from the bottom of the carrier. Thus, the locking tab 49 in FIG. 3 is provided with abutment shoulder portions designated by the numerals 58 and 59. In like fashion locking tab 41 is provided with shoulders 60 and 61 while complementary locking tab 50 comprises shoulders 62 and 63.

FIG. 4 is similar to FIG. 3 but depicts the parts in disengaged condition. FIG. 4 shows fold lines 64-66 formed at the bases of the locking tabs 40-42 respectively and the fold lines 67 and 68 formed at the bases of locking tabs 50 and 51, respectively. The fold lines 64-68 serve

to render the locking tabs flexible and thereby facilitate locking and unlocking although in some instances fold lines 64-68 could be eliminated.

The modifications of the invention as depicted in FIGS. 5 and 6 in general utilize cut lines which receive the corners or ends of complementary locking tabs and thus afford added strength and improved appearance. This feature also tends to prevent the tabs from being dislodged or torn due to engagement with an adjacent carrier or with some other object.

The arrangement of FIG. 5 is quite similar to FIG. 4 in that panel 14 is provided with square cornered locking tabs 69, 70 and 71 which are foldably joined along fold lines 72, 73 and 74, respectively, to the panel 14. For some applications of the invention fold lines 72-74 may be eliminated. In addition cut lines 75, 76 and 77 are formed in the locking tabs 69, 70 and 71, respectively. The cut line 75 diverges into a pair of auxiliary cut lines 78 and 79 and cut line 76 diverges into a pair of auxiliary cut lines 80 and 81. Cut line 77 diverges into a pair of auxiliary cut lines 82 and 83. The structure of panel 16 is virtually identical to that of panel 14. For example, locking tab 84 is foldably joined to panel 16 by fold line 85 and a cut line 86 is formed in locking tab 84. This cut line 86 diverges into a pair of auxiliary cut lines 87 and 88. In like fashion, locking tab 89 is foldably joined to panel 16 by a transverse fold line 90 and a cut line 91 is formed in locking tab 89 and diverges into a pair of auxiliary cut lines 92 and 93. As already pointed out it may be desirable in some instances to eliminate the fold lines 85 and 90.

In order to lock the panels 14 and 16 using the locks of FIG. 5, locking tab 84 is forced between locking tabs 69 and 70 so that the base 85 of tab 84 is between and in alignment with the bases 72 and 73 of tabs 69 and 70 and so that tab 84 is disposed over panel 14 and with tabs 69 and 70 disposed over panel 16. The lower left hand corner of tab 84 designated 94 is slipped through the slot 79 and is thus held down securely. The dotted line 79 on tab 84 is used to indicate the portion 94 which is slipped through slot 79 in panel 14. In like fashion the corner 95 of tab 84 is slipped through slit 89 in panel 14. Similarly tab 89 is moved between tabs 70 and 71 so that its base 90 lies between bases 73 and 74 of tabs 70 and 71 and generally in alignment therewith. The corners 96 and 97 of tab 89 are slipped through slits 81 and 82 respectively while end tab 98 is disposed with its corner 99 slipped through slit 83.

The locks on panel 14 have their corners interlocked in like fashion with slits in panel 16. For example the corners 100 and 102 of tab 71 are slipped into slits 101 and 93. In like fashion the corners 103 and 104 of tab 70 are slipped into slits 92 and 88. Corner 105 of tab 69 slips into slit 87. The other corner of tab 69 is slipped into a slit (not shown) and the remaining tabs on both panels are arranged as described in connection with tabs 69-71 and 84, 89.

In FIG. 6 panel 14 is joined to panel 16 by locking tabs 106 and 107 which cooperate with locking tabs 108 and 109. Slits 110 and 111 are formed in tab 106 while slits 112 and 113 are formed in tab 107. Likewise slits 114 and 115 are formed in tab 108 while slit 116 is formed in tab 109. When locked, the ends 117 and 118 of tab 108 are slipped through slits 110 and 113, respectively. As before the base of tab 108 lies between the bases of tabs 106 and 107 and in substantial alignment therewith. Of course the end 119 of tab 109 is disposed in slit 112. Ends 121 and 122 of tab 107 are received in slits 115 and 116 respectively while end 120 of tab 106 is slipped through slit 114, it being understood that all the locks on each of the panels 14 and 16 are similarly arranged when locked.

While fold lines may be used at the bases of tabs 106-109 such lines are not indicated in FIG. 6 and ordinarily will not be necessary.

While particular embodiments of the invention have

been shown and described, the invention is not limited thereto and it is intended in the appended claims to cover all such changes and modifications as fall within the true spirit and scope of the invention.

The embodiments of the invention in which an exclusive property or privilege is claimed are defined as follows:

1. An arrangement for interlocking adjacent edges of a pair of yieldable substantially coplanar panels, said arrangement comprising a pair of locking tabs formed on said edge of one of said panels and disposed in spaced relation to each other, abutment shoulders formed respectively on said locking tabs and extending into the space therebetween, there being a medial longitudinal slit formed in each of said locking tabs with the outer end thereof spaced from the outer tip of the tab, a complementary locking tab formed on said edge of the other of said panels and disposed in the space between said pair of tabs, a pair of abutment shoulders formed respectively on opposite edges of said complementary locking tab for engaging said abutment shoulders on said pair of locking tabs thereby to secure said panels against substantial relative movement, and a medial longitudinal slit formed in said complementary locking tab with the outer end thereof spaced from the outer tip of the tab.

2. An arrangement for interlocking adjacent edges of a pair of yieldable substantially coplanar panels, said arrangement comprising a pair of locking tabs formed on said edge of one of said panels and disposed in spaced relation to each other, abutment shoulders formed respectively on said locking tabs and extending into the space therebetween, there being at least one pair of slits formed in said one panel and disposed in generally diagonal relation to said locking tabs, a complementary locking tab formed on said edge of the other of said panels and disposed in the space between said pair of tabs, and a pair of abutment shoulders formed respectively on opposite edges of said complementary locking tab for engaging said abutment shoulders on said pair of locking tabs thereby to secure said panels against substantial relative movement, a part of each shoulder on said complementary locking tab extending into one of said slits.

3. An arrangement for interlocking adjacent edges of a pair of yieldable substantially coplanar panels, said arrangement comprising a pair of locking tabs formed on said edge of one of said panels and disposed in spaced relation to each other, there being a pair of medial slits formed respectively in said locking tabs and extending into said one panel, there being a pair of auxiliary slits in said one panel and connecting with each medial slit, abutment shoulders formed respectively on said locking tabs and extending into the space therebetween, a complementary locking tab formed on said edge of the other of said panels and disposed in the space between said pair of tabs, there being a third medial slit formed on said complementary locking tab and extending into said other panel, there being a pair of auxiliary slits in said other panel and connecting with said third slit, and a pair of abutment shoulders formed respectively on opposite edges of said complementary locking tab for engaging said abutment shoulders on said pair of locking tabs thereby to secure said panels against substantial relative movement, a part of each shoulder of said complementary locking tab being disposed in one slit of each pair of auxiliary slits in said one panel.

4. An arrangement for interlocking adjacent edges of a pair of yieldable substantially coplanar panels, said arrangement comprising a pair of locking tabs formed on said edge of one of said panels and disposed in spaced relation to each other, abutment shoulders formed respectively on said locking tabs and extending into the space therebetween, a complementary locking tab formed on said edge of the other of said panels and disposed in the space between said pair of tabs, and a pair of abutment shoulders formed respectively on opposite edges of said

complementary locking tab for engaging said abutment shoulders on said pair of locking tabs thereby to secure said panels against substantial relative movement, and there being cut lines formed in each of said panels and disposed generally in normal relationship to said edges of the associated panel for receiving adjacent parts of the shoulders of locking tabs formed on the other of said panels.

5. An arrangement for interlocking adjacent edges of a pair of yieldable substantially coplanar panels, said arrangement comprising a plurality of locking tabs formed in spaced relation along said edge of one of said panels, a pair of shoulders formed on opposite edges of at least some of said locking tabs, a plurality of complementary locking tabs formed in spaced relation along said edge of said other panel, a pair of shoulders formed on opposite edges of at least some of said locking tabs, said complementary locking tabs being disposed in staggered relation to said locking tabs and with the shoulders thereof disposed in engagement with the shoulders of said lock-

ing tabs to prevent substantial relative movement between said panels, and there being cut lines formed in at least some of said tabs and disposed lengthwise of said tabs and extending into the associated panel, said cut lines in each panel being adapted to receive a part of a locking tab formed on the other panel.
